SOUNDING TOP SPINNER

George Palken and Nathan Einis,
Dorchester, Mass.

Application September 9, 1946, Serial No. 695,712

4 Claims. (Cl. 46—67)

1

The present invention relates to a toy and, more particularly, a toy which combines an imitation gun and a top. The toy may operate primarily for the purpose of spinning the top which forms a part of it or it may serve both to spin a top and to produce a noise by impact of elements therein.

Besides the novel combination of a gun and a top-spinning toy, the invention resides in the construction of the mechanism and device wherein simple manual operation is provided both in cocking the spring and releasing the same for spinning the top and making the noise in imitation of the discharge of a gun. The present invention is simple, inexpensive in construction, may be readily assembled, and has durable wearing qualities.

In accordance with the present invention, a trigger manually operated is used both for cocking the gun or tensioning the spring and for the release thereof. The invention will be more fully described in the specifications below when read in connection with the drawings illustrating an embodiment of the same, in which Fig. 1 shows an elevation of the mechanism with the top in place, Fig. 2 shows a sectional view taken on the line 2—2 of Fig. 3, Fig. 3 shows a sectional view taken on the line 3—3 of Fig. 2, Fig. 4 shows a detailed section on the line 4—4 of Fig. 3, Fig. 5 shows a view similar to Fig. 3 with the mechanism in a different position of operation; Figs. 6 and 7 are similar to Fig. 5 with the mechanisms in different positions of operation, Fig. 8 shows a detail section taken on the line 8—8 of Fig. 2, and Fig. 9 shows a further detail of the invention.

In the drawings, the toy gun itself may be formed with two substantially similar casing members 1 and 2, which may be held together by a plurality of stay bolts, such as 3, 3', forming a casing within which the internal operating mechanism of the toy is contained. The gun may be shaped in the usual fashion of a repeating automatic, with the conventionally shaped barrel 4, handle 5, and trigger member 6. Besides this, the gun has externally a latching member 7, whose function and operation will be explained later. A top 8 which has a stem 9 is supported in an opening extending into the gun perpendicular to the axis of the barrel. The top is ejected by proper combined operation of the latching member 7 and the trigger 6, while the cocking or tensioning of the spring is accomplished by a reciprocal motion of the trigger 6. This will be evident from the description of the mechanism and operation of the toy.

2

Mounted longitudinally within the barrel chamber 11 is a bar 12 which at the forward end carries a rack 13, which is parallel to the rest of the bar 12, but offset slightly from the rest of the bar by means of a short angular piece 14, which joins rack 13 to the rest of the bar. Rack 13 engages the pinion 15 formed on the stem 9 of the top and turns the top stem as the rack is moved in the discharge of the top 8. The bar 12 is enlarged at its right end portion 18 which has formed therein a longitudinal slot 16 (see Figs. 3, 5, 6, and 7), which is engaged by the rod 17 passing through both walls 1 and 2 of the casing. The rod 17 also serves to pivot the trigger lever 6 with respect to the walls 1 and 2. The end of the bar 12 after the enlarged portion 18 is terminated in an angle element 19, to which a helical spring 20 and its axially positioned rod 21 are attached. The spring 20 envelopes at its other end a tube 22 riveted to the end of the gun at 23, while the rod 21 acts as a guide entering the tube 22 as indicated at 23'. The spring 20 is preferably fixed at the end of the gun where the tube 22 is held, but this is not always necessary since the gun is cocked by compression of the spring 20 and fires by expansion of the spring, so that as long as the spring does not leave the tube 22 it will operate successfully. The bar 12 is provided at its bottom edge in the section 18 with a series of spur teeth 24, which are engaged by the single projecting tooth 26 extending laterally from the top of the member 25. The member 25 is pivoted to the trigger lever 6 by means of the pin 27. The element 25 is shown in detail in Fig. 9. Besides the projecting arm or tooth 26, it also has a forward projecting arm 37 serving to release the bar latch, as will be explained, as well as an angular section 28 and 35 forming a connection with the latch 7 which is a part of the member 25. The member 25 is drawn towards the bar 12 so that the single tooth 26 engages the spur teeth 24 by means of the spring 30, one end of which hooks into the angular section 28 at 29 while the other end of the spring hooks around the shaft 17 at 31 over a sleeve on the shaft.

The lever 6 may be formed of a single piece of stock bent to form a channel having sides 32 and 33, through which the shaft 17 passes which is pivoted to the casing. At about the middle of the lever 6, there is a perforation through which is hooked one end of the spring 34, the other end of which is fastened to the wall of the gun at the pin 3', thus drawing the lower end of the lever 6 to the left as shown in Fig. 3. In this

manner, the normal position of the trigger lever 6 is that inclined in a forward direction as indicated in Fig. 3.

It should be noted in connection with the description of the member 25 that the inwardly projecting arm 36 rides either in the upper slot 43 or the lower slot 44 in the wall 1 of the gun. In the upper slot 43 the gun may be cocked by working the trigger back and forth while when the arm 36 rides in the slot 44 the gun is fired. The gun is prevented from being fired by means of the latching pawl 39, one end 49 of which engages the teeth 24, while the other end has an arm 38 which normally, except when firing, is free from the projecting arm 37 of the member 25. A spring 41 acting between the pawl 39 and the wall 2 holds the pawl up in engagement with the teeth 24. The pawl is provided with a hub element 42 by means of which the pawl is pivoted to the wall 2 of the frame of the gun.

At the forward end of the gun is a plate 45 against which the end of the bar 12 is shot to produce a loud noise as the top is spun out of the barrel.

The gun is loaded by inserting the stem 9 of the top through the holes 46 and 47 aligned in the bottom and top of the gun. A spring clip member 48 (Fig. 4) helps to retain the top in position until the winding is begun, by having its end prong 49 pressed against the stem 9 of the top. The loading position is shown approximately in Figs. 3 and 5. In this position, the bar 12 is out furthest to the left and the pinion 15 just begins to engage the rack 13 of the bar 12. Suitable spring members 50, 50 journaled in the walls 1 and 2 retain the rack 13 in its desired position. The bar 12 is forced to the right, as viewed in Fig. 3, by pulling the lower end of the trigger 6. The trigger 6, carrying the member 25, which is pivoted to it, engages in the teeth 24 and as the trigger is rotated counter-clockwise, the bar 12 is pulled backwards against the action of the spring 20. The pawl or latching bar 39 prevents the bar 12 from flying forward when the finger releases the trigger 6. When the trigger is released, the spring 34 draws the lower end forward or moves the trigger in a clockwise direction, so that it may be pulled backward again, pulling the bar 12 back still further. About three reciprocal motions of the trigger 6 will completely load the gun or draw the bar 12 back to compress the spring 20 to its fullest extent. During this motion, the safety latch or latch 7 is in the position indicated in Fig. 1 with the projecting member 36 riding in the upper slot 43. When, however, the latching member 7 is pressed downward or rotated about its pivoting point 27, the tooth or projecting arm 26 is withdrawn from the row of teeth 24 and instead the projecting element 37 is brought up beneath the projecting arm 38 of the pawl or latch 39. The pin 36 in this position rides in the slot 44 and the member 25 is inclined upwards at an angle, bringing the projecting arm 37 just beneath the arm or bar 38. In this position, when the trigger 6 is pulled or turned counter-clockwise, the projecting arm 37 engages the underside of the arm 38, pushing it upwards, the backward movement of the arm 37 thereby releasing the engaging end 40 of the pawl from the teeth 24. Since nothing further holds the arm 12 in this position, the spring 20 will force it forward as shown in Fig. 7, thus spinning the top and causing it to drop out of the gun while spinning. At the same time, the

contact of the end of the bar 12 with the plate 45 makes an impact similar to that of an explosive cap. Any other type of noise may, of course, be made if desired in a similar fashion.

5 The gun may be carried around loaded by retracting the bar 12 by moving the trigger 6 back and forth and then permitting the latch 7 to remain in a horizontal position in which the pin or arm 36 is engaged in the upper slot 43. Since all of the operating mechanism for the gun is covered and enclosed, there is no danger in any way for a child to get his hands caught either in the gun mechanism or in the gun hammer, since these elements or the equivalent thereof are entirely enclosed within the casing of the gun itself.

15 Having now described our invention, we claim:

1. In a toy of the type described for spinning a top, said toy having the form of a gun with an elongated barrel, a bar having a rack member at one end positioned in said barrel and adapted to be moved longitudinally in respect thereto, spring means operating with and against the bar, a trigger member having a fixed pivot with reference to said gun, a second member pivoted to said trigger member having an extending arm engaging teeth associated with said bar, a pawl normally engaging said teeth for holding said bar against the action of the spring and means for manual adjustment of said second member whereby when said trigger is pulled the pawl restraining the bar is removed from engagement with the teeth and the bar released.

2. In a toy of the type described for spinning a top, said toy having the form of a gun with an elongated barrel, a bar having a rack member at one end positioned in said barrel and adapted to be moved longitudinally in respect thereto, spring means operating with and against the bar, a trigger member having a fixed pivot with reference to said gun, a second member pivoted to said trigger member having an extending arm engaging teeth associated with said bar, a pawl normally engaging said teeth for holding said bar against the action of the spring, and means for manual adjustment of said second member whereby when said trigger is pulled the pawl restraining the bar is removed from engagement with the teeth and the bar released, said second member having a projecting arm engaging one of two connected slots in said casing, engagement in one slot permitting retracting of said bar, and in the other slot, release of said bar.

3. In a toy of the type described having the form of a gun with a loading operation and a discharging operation for spinning a top, a bar having a rack on a portion of its face, a top inserted in the gun to engage the rack for spinning, means mounting the bar to move longitudinally in the barrel of the gun, a spring mounted to act against one end of the bar, said bar having a series of teeth, a pawl positioned to engage the teeth to permit retraction of the bar against the spring and to restrain said bar from movement in the opposite direction, a pivoted trigger, a coupling cam pivoted with said trigger, means for positioning said cam in one of two positions, the first coupling the trigger with the teeth in the bar for reTRACTING the same against the spring when the trigger is operated in the loading operation and the second for disengaging the pawl when the trigger is operated in the discharging operation.

4. A toy of the type described having the form of a gun with a loading operation and a discharging operation for simultaneously spinning a top and making a noise comprising a bar having a

rack on a portion of its face, a bracket across the end of the gun within the barrel against which the bar strikes, a top inserted in the barrel engaging the rack and adapted to spin when the bar is impelled against the bracket, means mounting the bar to move longitudinally in the barrel of the gun, a spring mounted to act against one end of the bar, said bar having a series of teeth, a pawl positioned to engage the teeth to permit retraction of the bar against the spring and to restrain said bar from movement in the opposite direction, a pivoted trigger, a coupling cam pivoted with said trigger, means for positioning said cam in one of two positions, the first coupling the trigger with the teeth in the bar for retracting the 15 same against the spring when the trigger is operated in the loading operation and the second for

disengaging the pawl when the trigger is operated in the discharging operation.
